Filed Jan. 21, 1971, Ser. No. 108,691

Term of patent 14 years

Int. Cl. D8—03

U.S. Cl. D8—61

FIG. 1 is a top plan view of a housing for electric shears showing my new design;

FIG. 2 is a side elevational view thereof;

FIG. 3 is an elevational view from the forward end thereof;

FIG. 4 is an elevational view from the other end thereof; and

FIG. 5 is a plan view looking upwardly towards the bottom.

The design is symmetric from side to side along the longitudinal axis and the side not shown is a mirror image of the side shown.

I claim:

The ornamental design for a housing for electric shears, as shown and described.
